UNITED STATES PATENT OFFICE.

CHARLES C. SPENGLER, OF ROCKFORD, ILLINOIS, ASSIGNOR TO SPENGLER BROTHERS COMPANY, OF CHICAGO, ILLINOIS, A CORPORATION OF ILLINOIS.

PENCIL-SHARPENER.

1,204,604.

Specification of Letters Patent. Patented Nov. 14, 1916.

Application filed August 14, 1913. Serial No. 784,670.

To all whom it may concern:

Be it known that I, CHARLES C. SPENGLER, a citizen of the United States, residing at Rockford, in the county of Winnebago, State 5 of Illinois, have invented certain new and useful Improvements in Pencil-Sharpeners, of which the following is a specification.

My invention relates to pencil sharpeners, and refers particularly to that type of pencil sharpeners in which cylindrical rotary cutters having spiral cutting edges thereon are employed.

In my co-pending application, Serial No. 687,000, filed March 29, 1912, I have described a form of pencil sharpener which has many features in common with the pencil sharpener of the present invention.

My present invention relates particularly to a form of pencil sharpener in which a 20 pair of cutters is employed and to a point adjuster which is readily adjustable to vary the length of the point of a pencil which is sharpened, and which is provided with adjustable means for regulating its limit of 25 movement. Although my improved point adjuster may be used with any style of pencil sharpener, it is especially adapted for use in connection with my improved type of pencil sharpener in which a pair of cylindrical 30 cutters is employed. I am aware that it is old to use two cylindrical cutters in a pencil sharpener, but it is new, so far as I am aware, to employ a point adjuster in connection with such a pair of cutters, and 35 it is to the end of providing a practical mechanical embodiment of this combination that my present invention is directed.

These and other advantages of my invention will be more readily understood by reference to the accompanying drawing, which 40 shows a preferred embodiment of my improvements, and in which—

Figure 1 is a side elevation of my pencil sharpener, a portion of the casing being 45 removed in order to show the interior mechanism more clearly; Fig. 2 is a side elevation of the cutter frame used in my pencil sharpener, the cutters being removed for the sake of additional clearness; and, Fig. 3 is an enlarged side elevation of the point adjuster.

The pencil sharpener consists of a base plate 10 having an up-turned apertured end 11. Fastened to the base plate 10 is a casing 12, in which is rotatably supported the cutter frame 13 having attached thereto the

crank 14. By suitable mechanism, when the crank 14 is rotated not only is the cutter frame 13 itself rotated but the cylindrical cutters 15, 15 supported in said frame are also rotated on their own axes. Since the mechanism for accomplishing this result forms no part of my present invention, I will omit further detailed description thereof. Fitting within the casing 12 is the drawer 16, which is for the purpose of receiving the shavings caused by the sharpening of the pencil.

The pencil feeding device consists of a spring-controlled tube 17, having mounted thereon the head 18 provided with a suitable pencil holding chuck. The arm 19 extends downwardly into a suitable groove or slot in the base 10. When a pencil is to be sharpened the head 18 with its attached arm 19 and the tube 17 are bodily moved to the left from the position indicated in Fig. 1, a pencil is inserted in the chuck of the head 18, and the controlling spring causes the head 18 and its attached parts to then normally move to the right, thereby automatically feeding the pencil to the sharpening device proper. This feeding mechanism forms no part of my present invention.

The cutter frame 13 comprises the end disks 20 and 21 which are connected with each other by the partition 22. The partition 22 is provided with an opening or slot 23 through its central portion. Contained within this opening or slot is the guide block 24 provided with an enlarged end 25 which 90 abuts against the shoulder 26 of the slot 23 when the block reaches its limit of movement to the left, as indicated in Fig. 2. The guide block 24 may be secured in adjusted position by means of a screw or other 95 similar device extending through the partition 22, the head of such screw being normally concealed by means of the removable cover 27.

The point adjuster 28 is pivotally secured 100 to the partition 22 of the cutter frame 20 by means of the screw 29, this point adjuster, preferably being in the form of a bell-crank lever. The arm 30 of the point adjuster is preferably hook-shaped on its end 31, so 105 that the point of the pencil may always have a square bearing surface. The arm 32 of the point adjuster 28 has the slot 33 near its end, thereby forming a relatively narrow abutment member 34. The main portion of 110

the arm 32 is provided with a small lug 35, which engages in one of the cup-shaped depressions 36 in the partition 22.

The partition 22 is provided with the block support 37 preferably integral with the partition 22, the function of this block support being not only to assist in holding the block 24 in position but also to act as a stop surface for limiting the movement of 10 the point adjuster 28 in the manner to be presently described.

Having thus described the various parts employed in my invention, the operation of the same may now be readily understood:

- 15 When a pencil (indicated in dotted lines by 38 in Fig. 2) is brought into operative relation with the sharpener, the point of the pencil is automatically forced to the right by the action of the spring-controlled chuck 20 head 18. The crank 14 being rotated, the pencil is sharpened by the joint action of the cutters 15, 15, which engage as much of the pencil as is allowed to project through the slots 39 of the guide block 24. The 25 pencil continues to be moved to the right until its point engages the hooked end 31 of the point adjuster. When this takes place it will be evident that the further sharpening of the pencil will cease, since 30 the pencil can no longer be fed to bring new portions into engagement with the cutters 15. When it is desired to change the length of the point of a pencil to be sharpened, the arm 32 of the point adjuster 28 is moved 35 either toward or away from the block support 37 preferably by means of the handle 40. The point adjuster is held in any desired position by the engagement of the small lug 35 with one of the cup-shaped depressions 36 in the partition 22. When the 40 arm 32 is moved toward the block support 37 to such an extent that the abutment member 34 engages the outer side of the block support 37, it will be evident that no further 45 inward movement of the arm 32 can take place. By this movement the arm 30 has been moved to the right into the position at which the maximum length of pencil point is obtained. Since the arm 30 is located 50 between the two cutters 15, it will be evident that it is very desirable to limit the movement of the arm 30, as in this way not only is the danger of sharpening a pencil to a needle point avoided but also the arm 30 55 is prevented from being brought directly into engagement with the cutting surfaces of the cutters 15. The outward movement of the arm 32 and the corresponding movement to the left of the arm 30 are limited 60 by the engagement of the arm 30 against the end of the guide block 24.

As the cutters 15 are reduced in diameter

by sharpening, it is desirable to be able to vary the limit of movement of the point adjuster, and in order to accomplish this I 65 adjust the abutment member 34 of the point adjuster to suitable position. If it is desired to decrease the limit of the movement of the point adjuster, a screw driver or other similar tool is inserted in the slot 33 70 and the abutment member 34 is spread slightly, as, for example, into the position indicated in dotted lines in Fig. 3. On the other hand, if it is desired to increase the limit of movement of the point adjuster so 75 that the arm 30 may be moved farther to the right, the abutment member 34 is bent toward the main portion of the arm 32, as, for example, by means of a pair of pincers. In this way not only is the point adjuster 80 readily adjustable within its fixed limit of movement, but this limit may also readily be changed when desired.

It will be apparent to those skilled in the art that many changes could be made in the 85 detailed construction of the parts which I have described without departing from the spirit or scope of my invention.

What I claim is:

1. In a pencil sharpener, the combination 90 of a rotary cutter frame having a stop surface thereon, a rotary cutter carried by said cutter frame, and a point adjuster pivotally mounted on said frame, said point adjuster comprising a lever having one arm thereof 95 adjacent to said cutter and adapted to limit the feeding of a pencil to be sharpened and the other arm of said lever having a slot in the end thereof, with a readily bendable integrally formed abutment member adjacent 100 to said slot, said abutment member adapted to be brought into engagement with said stop surface, whereby the limit of movement of said lever is adjustably controlled.

2. In a pencil sharpener, the combination 105 of a rotary cutter frame having a stop surface thereon, a pair of rotary cutters carried by said cutter frame, and a point adjuster pivotally mounted on said frame, said point adjuster comprising a bell-crank lever having one arm thereof projecting between said 110 cutters and adapted to limit the feeding of a pencil to be sharpened and the other arm of said lever having a slot in its end, with a readily bendable integrally formed abutment member adjacent to said slot, said abutment member adapted to be brought into engagement with said stop surface, whereby the limit of movement of said point adjuster may be adjustably controlled.

CHARLES C. SPENGLER.
